UNITED STATES PATENT OFFICE.

CHARLES F. TRAVALLED, OF NEW ROCHELLE, NEW YORK, ASSIGNOR TO ARTHUR GREENFIELD, INC., OF NEW YORK, N. Y., A CORPORATION OF NEW YORK.

SOFFIT-CLIP.

1,115,749.

Specification of Letters Patent.

Patented Nov. 3, 1914.

Application filed April 22, 1914. Serial No. 833,581.

To all whom it may concern:

Be it known that I, CHARLES F. TRAVALLED, a citizen of the United States, and resident of New Rochelle, Winchester county, State of New York, have invented certain new and useful Improvements in Soffit-Clips, of which the following is a specification.

My invention relates to that type of devices commonly known as soffit-clips and has for its object to provide a device of this character which will at all times adequately and reliably support the concrete or other coalescent material forming the soffit and which will assure a reinforced soffit of maximum strength.

My improvement further contemplates the provision of a soffit-clip which is simple and economical to manufacture, occupies very little space before being assembled for use, is very strong and readily and quickly placed in operative position and which does not interfere with the free flow of the material in tamping thus preventing the formation of air spaces and insuring a perfect bond.

My invention will be fully described hereinafter and the features of novelty will be pointed out in the appended claims.

Reference is to be had to the accompanying drawings in which—

Figure 1 is an inverted plan view of a beam with my improvement applied thereto; Fig. 2 is a side elevation thereof; Fig. 3 is an end view and Fig. 4 is an enlarged detail view of one of the elements comprising my invention.

In the drawings, I have shown my improved clip applied to an I-beam, it being understood that this is only an example and that said clip may be used to advantage in many other ways.

My improved clip construction comprises end members 5 each shaped to form opposite end loops 6 and clamping fingers 7 and further included a series of duplicate additional or intermediate members 8, each having one end bent into a hook 9 and the opposite end shaped to form a loop 10 similar to the loops 6 and clamping fingers 11 corresponding to the fingers 7. These various members which may be constructed of wire or any other suitable material, are extremely simple and cheap to manufacture and in their initial condition are disconnected and separate

from each other thus occupying a minimum of space and in consequence are capable of being readily stored and conveniently shipped.

In applying the device an end member 5 is placed upon the beam 12 for instance near an end thereof with the loops 6 in engagement with the lower surface of the beam flange 13 and the clamping fingers 7 for instance projecting upwardly at opposite edges of said flange as indicated in dotted lines in Fig. 3. After the said end member has been properly positioned the clamping fingers 7 may be turned down into engagement with the upper surface of the beam flange 13 to coöperate with the loops 6 and securely clamp the said end member 5 in position. An additional or intermediate member 8 is now placed in position by engaging the hook 9 thereof with one of the loops 6 and extending said member 8 beneath the beam 12 at the desired angle with the loop 10 also in engagement with the lower surface of the beam flange 13. This intermediate member 8 may also be secured upon the beam by bending the clamping finger 11 firmly into engagement with the upper surface of the beam flange 13 in the same manner as the fingers 7. A second additional or intermediate member 8 is now placed in position by engaging its hook 9 with the loop 10 of the preceding member 8 and said second member 8 is extended beneath the beam at the desired angle and in the opposite direction to the first member 8. The second member 8 may be similarly secured in position by bending its clamping finger 11 into engagement with the flange 13 after which additional intermediate members 8 may be successively connected together and secured in position to form a zig-zag structure of the desired length.

It will be seen, in the finished structure, that the loops 6 and 10 serve to space the members 5 and 8 respectively from the surface of the beam, the completed structure providing a reliable reinforcement for the soffit at the points of greatest tension without in any way interfering with the free flow of the concrete or other material in tamping thus insuring a perfect bond throughout. The loops 6 and 10 in combination with the fingers 7 and 11 also form more or less resilient clamps whereby the opposite edges of the flange 13 are firmly

gripped and the device is securely maintained in operative position. It will, of course, be understood that instead of bending the fingers 7 and 11 as described the same may be initially shaped as shown in solid lines in Figs. 3 and 4 and simply slipped or hooked over the edges of the flange 13 during the assembling operation.

It will at once be apparent that the members 11 may be readily adjusted at different angles to vary the spacing and to secure the best results in each instance, the loops 10 being capable of being easily adjusted or bent relatively to the members 8 so as to extend at substantially right angles to the major axis of the beam 12 as is preferred. In my improved structure the various clip members are interlocking whereby continuity of construction is secured and the structure before being set up occupies very little space and is thus easily stored and shipped. In addition to the above, no special calculations or measurements are required to insure a proper combination of my improved structure with for instance a beam, and the same may be readily placed in position by unskilled labor.

Various changes in the specific form shown and described may be made within the scope of the claims without departing from the spirit of my invention.

I claim:

1. The combination of a supporting means, a plurality of separate members, co-operating means on said members whereby the latter are detachably connected together to form a continuous structure for reinforcing and supporting a soffit and means for securing said members in operative position upon said supporting means.

2. The combination of a supporting means, an end member connected with said supporting means, a plurality of additional separate members, co-operating means on all 45 of said members whereby said additional

members are detachably connected with said end member and with each other to form a zig-zag continuous structure adjacent to said supporting means for reinforcing and supporting a soffit and clamps for clamping 50 said additional members in operative position upon said supporting means.

3. The combination of a beam having a flange, a plurality of members arranged adjacent to the surface of said flange, loops 55 formed integral with said members for spacing the latter from said flange surface, hooks on said members adapted to engage said loops whereby said members are connected together to form a continuous structure and means co-operating with said loops for clamping said members upon said flange.

4. The combination of a beam having a flange, an end member arranged beneath said flange and extending transversely 65 across the same, integral loops at opposite ends of said end member for spacing the latter from the surface of the flange, fingers co-operating with said loops for clamping said end member upon said flange, a plurality 70 of additional members extending zig-zag adjacent to said flange surface, a loop at one end of each of said additional members for spacing them from said flange surface, a hook at the opposite end of each additional member, the hook of one additional member being engaged with a loop of the end member and the hooks of successive members being engaged with the loops of successive additional members to form a 80 continuous structure and fingers adapted to co-operate with the loops of said additional members to secure the latter upon the flange.

In testimony whereof I have hereunto set my hand in the presence of two subscribing witnesses.

CHARLES F. TRAVALLED.
